CLAIM

The ornamental design for a kiosk, as shown and described.

DESCRIPTION

FIG. 1 is a front perspective view of a kiosk;
 FIG. 2 is a front view thereof;
 FIG. 3 is a back view thereof;
 FIG. 4 is a left side view thereof;
 FIG. 5 is a right side view thereof;
 FIG. 6 is a top plan view thereof; and,
 FIG. 7 is a bottom plan view thereof.

The broken lines shown in the drawings are for illustrative purposes only and form no part of the claimed design. The shade lines in the figures show contour and not surface ornamentation.

1 Claim, 6 Drawing Sheets(56)
